ATTACHMENT-PLUG FOR ELECTRIC WIRES.

1,248,421.

Specification of Letters Patent. Patented Nov. 27, 1917.

Application filed September 13, 1916. Serial No. 119,844.

To all whom it may concern:

Be it known that I, CHARLES F. TORÉN, a citizen of the United States, and a resident of Springfield, in the county of Hampden and State of Massachusetts, have invented a new and Improved Attachment-Plug for Electric Wires, of which the following is a full, clear, and exact description.

This invention relates to electrical appliances and has particular reference to attachment means for electric extension devices or the like.

The primary object of the invention is to provide a plug for extension wires, lamps or other electrical appliances adapted to operate with a screw threaded standard socket, the connection being made by a simple push or plunge of the plug into the socket.

Another object of the invention is to improve the construction of extension plugs with respect to the means for securing the extension wires thereto, providing for a direct pull upon the wires for releasing the plug, without any danger of breakage or disconnection of the wires.

With the foregoing and other objects in view, the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a vertical sectional view of a socket having my improved plug secured therein;

Fig. 2 is a vertical longitudinal section of my improved plug on the line 2—2 of Fig. 1;

Fig. 3 is an end view of the plug as seen on the line 3—3 of Fig. 2;

Fig. 4 is a transverse section on the line 4—4 of Fig. 2; and

Fig. 5 is a plan view of the inner end of the plug core.

Referring now more particularly to the drawings, I show in Fig. 1 a standard socket 10 having a threaded contact cup 11 with metallic connection in the usual way with a wire A. Said socket also has a center contact 12 with metallic connection with the

wire B. These parts are or may be of conventional nature and I refer to them only to make clear the operation of my new devices.

My improved plug is shown as a pole at 13 and comprises a core 14 of porcelain or other suitable insulation. 15 indicates a center contact pin having at its outer end a rigid metallic head 16 lying within a recess 17 in the end of the core. A metal contact 18, adapted to engage the center contact 12 of the socket, is slidably fitted over the head 16 and has its inner edge spun thereover, as shown at 19, to prevent separation of the contact 18 from the center pin. A spring 20 acting outwardly upon the contact insures proper engagement with the contact 12, but permits inward movement of the resilient contact.

The base portion of the plug comprises an inner sleeve 21 having a flange 22 at its inner end lying in a plane perpendicular to the axis of the plug and having at its outer end a flange 23 having a down turned margin 24. The metal base portion of the plug also includes an outer sleeve 25 indicated as split into three similar longitudinal sections. Each section of this sleeve comprises an inwardly projecting flange 26 at its inner end and a longitudinally extended lip 27 at its outer end. The flange 26 lies upon the flange 22 of the sleeve 21 and the lip 27 lies between the edge 24 and the main portion of the inner or fixed sleeve 21. The sleeve 25 as a whole is screw threaded to simulate the threading of the socket 11, and hence in the main corresponds to the usual extension plug or lamp base electrically considered.

Each part of the sleeve 25 is acted upon by one or more springs 28 carried by the fixed sleeve 21 and acting outwardly on the sleeve 25, the outward movement of the sleeve 25 being limited by the rim 24 at one end and the sleeve 29 at the other. The sleeve 21 is fixed rigidly upon the core and the rotation of the split sleeve 25 is prevented by lugs 30 struck outwardly from the flange 22, and lugs 31 struck inwardly from the flange 23. The lugs 30 and 31 project radially between adjacent members of the sleeve 25, and not only prevent rotation of the sleeve 25 as a whole, but serve also to keep each section of the sleeve in proper position.

The sleeve 25 is connected by plate 40, rivet 41 and a binding post 32 with a wire A' and the center contact pin 15 is electrically connected through a plate 33 and binding post 34 with the other wire B'. These wires A' and B' at their ends lie in channels 35 and 36 respectively, formed in the inner end of the core and extending from the binding posts 32 and 24 in the direction 10 in which the cap 38 is screwed on (see Fig. 5) and thence pass out through a hole 37 in the cap 38 secured upon the sleeve 29. The cap has a central hub 39 which serves to grip these wires snugly against the adjacent end of the core, independently of the electrical connections at 32 and 34, thereby relieving all strain which may be put upon the wires from the binding posts. The sleeve 29 being fastened by means of a rivet 20 41 to the inner end of the core and the cap 38 being screwed firmly thereon, the wires will be amply bound in the place indicated for all practical purposes. Since this plug is adapted particularly for use in connection 25 with lamp sockets having shades and making access to the plug inconvenient for manipulation, it is intended that the removal of the plug may be effected simply by drawing or jerking upon the wires.

30. To connect the plug to the socket, all the operator has to do is to simply thrust or shove the base portion thereof directly into the socket. The round outer end of the sleeve 25 will ride easily over the threads 35 of the socket piece and the springs 28 will permit sufficient inward radial movement of the portions of the sleeve 25 to enable the crests of these portions to ride over the crests of the member 11. The contact piece 40 18 will thus be brought into proper engagement with the center contact 12, completing the electrical connections. The coöperating threads of the two main parts will serve in the usual way to hold the parts together, but 45 while the springs 28 are sufficiently strong to thus hold the parts together, they will permit the withdrawal of the plug by direct pull thereon through the wires. This device is comparatively simple and is thoroughly 50 practical and reliable in use and may be manufactured and put on the market at a low cost.

I claim:

1. The herein described attachment plug 55 comprising a core, a center contact pin secured therein, a resilient contact slidably connected to the outer end of the pin, a pair of sleeves fitted around the core, one of the sleeves being fixed and the other comprising 60 a plurality of radially movable sections, resilient means tending to force the sections outwardly with respect to the fixed sleeve, and a pair of electrical contacts connected

with said center pin and said sleeve members.

2. In an attachment plug, the combination of a core of insulation, a center contact carried thereby, a contact sleeve surrounding the core and insulated thereby from the center contact, said sleeve comprising a plurality of independently radially movable sections, means to prevent circumferential movement or displacement of any of these sections, a pair of extension wires, means to electrically connect the wires respectively to the sleeve and the center contact, and means independent of the connecting means aforesaid to clamp said wires to the end of the core to relieve said electrical connections of the wires from strain.

3. In an attachment plug of the character set forth, the combination of a core of insulation, a center contact pin fitted therein, a pair of sleeves surrounding the core, one of the sleeves being fixed in position thereon and having inner and outer end flanges, the other sleeve comprising a plurality of independently movable sections, having their ends fitted for movement along said flanges, means to limit the movement of the sections substantially to radial movement with respect to the core, and electric terminals connected respectively to said center pin and sleeve structure.

4. In an attachment plug, the combination of a core having a cavity in its outer end, a fixed center contact pin extending through the core and having a rigidly connected metallic head located in said cavity, a resilient contact slidably fitted to said head and projecting beyond the core, contact sleeve devices surrounding the core and insulated thereby from the center pin and its contact, and a pair of electric terminals associated respectively with the pin and said sleeve devices.

5. In an attachment plug of the character set forth, the combination of a core of insulation, a center contact carried thereby, a fixed sleeve surrounding the core and having end flanges projecting outwardly therefrom in parallel planes perpendicular to the axis of the core, each of the flanges having a series of lugs projecting toward the other flange, an outer sleeve comprising a plurality of independent sections movable toward or from a fixed sleeve, each section having its ends lying between adjacent flange lugs, said section being held from circumferential movement by said lugs, means tending to force the sleeve sections outwardly, means to limit said outward movement, and electric terminals associated respectively with the center contact and said sleeve structure.

CHARLES FRITHIOF TORÉN.
